UNITED STATES PATENT OFFICE

CHARLES ALGERNON PARSONS AND JESSEL ROSEN, OF NEWCASTLE-ON-TYNE, ENGLAND; SAID ROSEN ASSIGNOR TO SAID PARSONS; KATHARINE PARSONS, VINCENT THOMPSON, AND FREDERICK GORDON HAY BEDFORD, LEGAL REPRESENTATIVES OF SAID CHARLES ALGERNON PARSONS, DECEASED

BRUSH GEAR FOR DYNAMO-ELECTRIC MACHINES

Application filed March 19, 1929, Serial No. 348,157, and in Great Britain April 20, 1928.

The invention relates to brush gear for dynamo-electric machines, the object of the invention being to provide a construction of such brush gear which shall be simpler and cheaper in construction and adjustment, and at the same time more efficient than brush gear constructions now in use.

In multi-polar dynamo-electric machines, the usual method of insulating the brush arms from the rocker necessitates many expensive insulating joints and copper connections between the brush arms and the connecting rings, together with heavy copper connections to the main terminals, and the setting of the brush arms in correct alignment with the commutator segments is difficult. The present invention consists in an improved brush gear construction which overcomes these difficulties and secures other important advantages set forth hereafter.

For a full understanding of the invention, a detailed description of constructions embodying the invention in preferred forms will now be given in connection with the accompanying drawings forming a part of this specification, and the features forming the invention then be specifically pointed out in the claims.

Referring to the accompanying drawings, which are to a certain extent of a diagrammatic nature:—

Figure 1 shows an elevation of a dynamo having a two-part commutator fitted with one form of brush gear in accordance with the present invention;

Figure 2 is a part end view to a larger scale of the brush gear shown in Figure 1;

Figure 3 being a cross-section through the rockers and adjacent parts on the line 3—3 of Figure 2; while finally

Figure 4 shows a corresponding cross-section to a smaller scale of a modified form in which the rocker carrier is formed in halves insulated from each other.

In carrying the invention into effect according to one form as shown in Figures 1 to 3 applied by way of example to a heavy-current low-voltage D. C. dynamo having a two-part commutator, A, A, the armature is indicated at B and the magnets at C.

The rocker comprises two juxtaposed circumferential rings, G, H, of cast iron separated from one another by the insulation, N, and bolted together by the insulated bolts, P; a spaced series of channel-like elements, G¹, H¹, is incorporated in each ring so that the two series are in imbricated relation to one another, these elements G¹, H¹, each carrying a pair of radially-running brush arms, E and F, one arm on each side, on which are mounted the brushes, D, for the two parts of the commutator.

The rocker faces h, h, to which the brush arms E, E, are secured are in two aligned series as shown, one ring carrying all the positive brushes and the other ring all the negative brushes, while the positive and negative brushes are arranged alternately as seen in end view, (see Figure 2).

The rocker carrier, L, of hollow annular form carries the rocker rings G, H, by help of insulated local facings, J, or, alternatively, (see Figure 4) the rocker carrier may be divided into two parts, L¹, L², separated circumferentially by insulation, U, in the same way as the rocker and both insulated from earth.

Any suitable means, such as T (Figure 2) also insulated, is provided for the adjustment of the rocker when the complete plant is in operation.

Preferably, each part of the gear described, for ease of assembly, is made in the usual manner in halves (see Figure 2) with a horizontal joint, K, the halves so formed being electrically connected.

If desired; each part of the brush rocker may be divided into arcuate lengths for ease in construction and assembly, while in some cases a less number of such lengths than are required to complete the ring may be used.

By virtue of the preferred form of the invention, the following advantages are obtained in combination:—

(a) A simple mechanical construction in which the parts are readily machined so that when assembling little or no adjustment of the brush arms is necessary;

(b) Separate insulation for each brush arm is eliminated;

(c) Connecting rings or leads usually of copper between all the positive and all the negative brush arms are not required;

(d) The rockers are further away than in usual constructions from the commutator and there is consequently less danger of flashing-over due for example to short circuits;

(e) The better mechanical construction provides for a more effective method of insulating the rockers and gives increased electrical leakage surfaces;

(f) The section of the rockers when of cast iron is sufficiently large to carry the current to the terminals instead of using massive copper connections.

Various alterations can be made in the details of the gear above set forth without exceeding the scope of the present invention.

What is claimed is:—

20 1. In combination in brush gear for dynamo-electric machines, a carrier frame, a pair of juxtaposed and insulated rockers movable on said frame and each having bracket-like members which are imbricated 25 in relation to the bracket-like members of the other rocker, a pair of oppositely-extending brush-carrying arms associated with each of said bracket-like members together with positive brushes mounted on those brush-carrying 30 arms associated with the bracket-like members of one of said juxtaposed rockers and negative brushes mounted on the brush-carrying arms associated with the bracket-like members of the other of said juxtaposed 35 rockers.

2. The combination of parts claimed in claim 1, in which said carrier frame is of ring-like form and is divided circumferentially into two parts insulated from one another.

3. The combination of parts claimed in claim 1, in which the bracket-like members are of channel section with aligned faces for the accommodation of said brush-carrying arms.

In testimony whereof we have signed our names to this specification.

CHARLES ALGERNON PARSONS.

50 JESSEL ROSEN.
